UNITED STATES PATENT OFFICE.

SAMUEL N. GOODMAN, OF PHILADELPHIA, PENNSYLVANIA, ASSIGNOR TO
FRIEDBERGER-AARON MANUFACTURING COMPANY, OF PHILADELPHIA,
PENNSYLVANIA, A CORPORATION OF PENNSYLVANIA.

DESIGN FOR LACE EDGING.

49,210.

Specification for Design.

Patented June 20, 1916.

Application filed April 10, 1916. Serial No. 90,260. Term of patent 7 years.

To all whom it may concern:

Be it known that I, SAMUEL N. GOODMAN, a citizen of the United States, residing in Philadelphia, county of Philadelphia, and State of Pennsylvania, have invented a new, original, and ornamental Design for Lace Edging, of which the following is a specification, reference being had to the accompanying drawings, which form a part thereof.

The same comprises a heading or sewing-on edge *a*, a body *b* and an ornamental scallop forming a tip or border *c*. The body *b* is composed of a number of longitudinally extending chain threads united by relatively fine cross threads. The body comprises alternating sections *b'* and *b''*, each section extending from heading to border. In sec-

tions *b'* the cross threads extend directly across the fabric, or at right angles to the direction of extension of the longitudinal threads. In sections *b''* the cross threads extend diagonally between adjacent longitudinal threads, the same being arranged in pairs the two threads of which intersect.

I claim—

The ornamental design for a lace edging, as shown and described.

In testimony of which invention, I have hereunto set my hand, at Philadelphia, on this 6th day of April, A. D. 1916.

SAMUEL N. GOODMAN.
